UNITED STATES PATENT OFFICE.

HUGO BREMER, OF NEHEIM, GERMANY.

ELECTRIC-ARC LAMP.

SPECIFICATION forming part of Letters Patent No. 684,407, dated October 15, 1901.

Application filed November 2, 1900. Serial No. 35,275. (No model.)

To all whom it may concern:

Be it known that I, HUGO BREMER, a subject of the Emperor of Germany, residing at Neheim-on-the-Ruhr, in the Province of Westphalia, Germany, have invented a new and useful Improvement in Arc-Lamps, of which the following is a specification.

In arc-lamps with carbon pencils placed pointing downward and in which the luminous arc expands downward in fan fashion vibration and fluctuation of the arc may very easily occur, because the arc has nothing to steady it, while the ascending atoms of air constantly tend to force it upward. Owing to the high temperature of the arc, which would soon fuse any substance, either wholly or partially, and would too much obstruct the emission of light, it was hitherto found impossible to confine the arc. These disadvantages are obviated in the arrangement forming the subject-matter of the present invention by causing the arc *b*, Figures 1 and 2, between the carbon-points *a a'* (which arc is powerfully depressed owing to electrical conditions or by means of magnetic arrangements for projecting it downward) to be steadied by causing its lateral edge to bear against the sides of a hollow cylinder or reflector *c*. The latter must therefore be of comparatively small dimensions, or else it must be contracted or provided with extensions *d* in the parts facing the edges of the arc. The emission of light will then remain unobstructed on the two large lateral surfaces. As the temperature is considerably lower at the sides of the arc than at the apex, which in this case remains perfectly free, the risk of fusion of the steadyng extensions is materially reduced. It may be further reduced to a minimum by admixing with the carbon a large percentage of such substances as are not themselves liable to combustion, thus considerably reducing the temperature of the arc. Among such substances I may mention the alkaline earthy metals and their salts or the salts of the metalloids—such as, for instance, silicon, alumina, calcium combinations, &c. While the heat of the arc of ordinary carbons is such as scarcely any material can stand, the temperature may by the aforesaid means be reduced sufficiently far to render such applications possible in the manner stated above. In the case of carbon pencils

placed one above the other only one shoulder *d'*, Fig. 3, may be employed, as in this position the arc has of itself an upward tendency. 55 In any case the support given to the arc by the solid surfaces, as above, exerts upon it an essential steadyng effect and imparts to it a greater stability without impediment to the emission of light or fusion of the parts 60 brought into contact with the arc. At the same time the effect is increased if simultaneously with the shoulders for steadyng the arc a magnetic field *e* is applied which will continually project the arc against these shoulders, 65 because the shoulders themselves, though preventing the arc from expanding outward—that is to say, becoming too large—cannot protect it against creeping inward or becoming too small; but care must be taken to insure 70 that the parts *d* of the reflector are effectively insulated, as otherwise secondary arcs might be formed between the edges or limbs of the arc and the parts *g* and a partial discharge of the branch current may take place by its passing from the edge or limb next to the positive carbon through the metal to the edge or limb near the negative carbon and thence back into the arc and to the negative carbon. This is impossible if the parts are insulated or made 75 of non-conducting material.

For the purpose of producing a magnetic field acting upon the arc in coöperation with the parts *d* I formerly proposed the arrangement described in my application Serial No. 85 23,783. In this connection I laid particular stress on the position occupied by the extensions with regard to the arc, because a circumstance to be considered is that the arc may sometimes incline half-way to one 90 side in consequence of draft or through some such cause, and it may then happen that while the position of the extension-pieces or pole-pieces hitherto tended to depress the arc entirely different parts of the extension-pieces may exert a magnetic action on the arc from the moment when it inclines half-way to one side, thus propelling it in the opposite direction—that is to say, upward. 95

The arrangement shown in Figs. 4 and 5 100 has been found to be the best position for the extension-pieces. In this arrangement the two extension-pieces *f* of the two poles are placed obliquely or else arranged hori-

zontally at the sides of the arc, above or below the latter—that is say, as compared with the former position the only point to which importance is attached is that the two ends 5 instead of being vertical are placed obliquely, or, better still, horizontally, and do not turn upward toward the regulating-magnet until at some distance from the arc, the arrangement being such that the lines of force are 10 not directed quite vertically, but only approximately vertically to the direction of the arc. Of course two permanent magnets or electromagnets might also be similarly arranged laterally to the arc; but in any case 15 the direction of the two pole ends or horns acting on the arc must have the above-mentioned position. Experiments have shown that the best action of the magnet upon the voltaic arc is obtained when arranging the 20 magnet or its pole-pieces or generally a magnetic field in such a manner below the carbon-points that the lines of force are operating exclusively upon the lower portion of the arc, so that the same is pulled downward by said 25 magnetic field and prevented from being overturned. However, it will also suffice if one single horizontal projection or horn f' only of the magnet is arranged parallel to the direction of the arc at the side thereof, as in Fig. 30. It will likewise suffice if one extension-piece f^2 is carried all around the arc, Fig. 7. In both cases the lines of force of the pole will strike the luminous arc obliquely. Even if the two poles $f^2 f^3$ of the magnetic field are 35 placed opposite each other at the side of the luminous arc, Fig. 8, so that the lines of force run directly parallel to the luminous arc, it will be found that the arc is impelled vertically downward. The lines of force have in 40 all cases a different direction with regard to the downward-driven arc, and from this it follows that the direction of the lines of force has no influence upon the direction in which the arc is deflected. It is therefore of im- 45 portance that the electromagnetic excitement resulting from the main magnet is directed parallel to the direction of the arc if the latter is burning as usual, whereupon the arc is deflected vertically up or downward, according 50 to the direction of the flowing magnetism. A proof of the correctness of this latter statement is supplied by the circumstance that it is possible even (see Fig. 9) to close the two pole ends magnetically, whereby any polarization 55 is done away with in the magnetic field created when, so to speak, the magnetic fluid emanates from the exciting-magnet only on both sides of the arc in a direction parallel to the latter.

60 In arc-lamps in which a regulating system is applied consisting of a series magnet and a shunt-magnet, as stated in a former patent specification of mine, the magnet extension-pieces on the series coil x , Fig. 9^a, are 65 best arranged below the arc and those of the shunt-coil y above. If, then, the arc recedes too far upward, it will be placed in closer

proximity to the series magnet and farther removed from the shunt-magnet. The influence of the latter will therefore decrease, 70 while that exerted by the former on the arc will increase, thus propelling the arc downward again.

In the arc-lamps hitherto described the carbons are supposed to be placed parallel or at 75 an acute angle to each other, and such carbons only are to be used which will form a hard non-conductive slag. The ignition of the carbons or so-called "striking of the arc" will therefore involve difficulties in so far as 80 it cannot be effected with certainty by simply moving the carbon-points toward each other, because the slag deposited on the lateral margins of the carbon pencils, Fig. 10, will prevent the necessary contact. I therefore propose to arrange between the carbons converging toward each other a metallic piece 85 g , which is removed from the carbons while the lamp is not alight. When the carbons, however, are approached to each other or 90 when the aforesaid metallic piece is moved downward, so that in the narrowing space between the carbons it must finally touch their lateral margins, the contact will be brought about, as indicated in the drawings by "dot- 95 and-dash" lines, above the slag zone. When the arc, once struck, is propelled downward, owing to the position of the carbon-points or in consequence of the repelling influence of a magnet, &c., the issuing points of the arc 100 will clear away the slag before them in their downward progress, so that the arc will constantly maintain contact and continue steadily until it has reached the extremities of the carbon, when it will remain stationary. 105

Figs. 11 and 12 of the accompanying drawings show an arc striking or igniting device which is based on the principles described before. It consists of a wedge-shaped primer h , which, actuated by the current of the lamp, 110 is brought between the carbons by means of a lever h' . It is desirable to position the primer in such a manner that the lever h' cannot remove the primer immediately after the contact between primer and carbon takes 115 place but remain in contact a short time to establish the striking of the arc with certainty. This end is obtained by connecting the lever h' , Fig. 11, with the primer h by a spring i . This connection has the effect that 120 when the lever is already acted upon by the current, so as to tend toward withdrawing the primer, the spring i will yield in the first place, thus causing the contact between the carbons and the primer to continue for a short 125 space of time. This arrangement insures, more especially in the case of various lamps grouped in series, that there is not a long-continued rattling noise or "pumping" in the lamp before ignition has taken place throughout; but after the arc in the first lamp has 130 been struck sufficient time is afforded to all the other lamps to ignite likewise, so that contact has been generally established through-

out before the first lamp on its part withdraws the primer from contact with the carbons. Such an igniter joined to its lever with the interposition of a spring may also be arranged 5 so as to protrude obliquely from below through the reflector, Fig. 13, and it may, moreover, be duplicated (see Figs. 14 and 15) and provided with a separate primer-point k for each carbon, so that each primer-point is brought 10 into contact with the respective carbon-point and owing to the elasticity of the spring is enabled to adapt itself to any irregularities, so as to establish a circuit through the medium of the two priming-levers $h' h^2$, which 15 are connected so as to make a "short circuit." The precipitates deposited above the slag on the carbons may also be removed by causing the primer to strike the carbons after the fashion of a hammer in the manner indicated in Fig. 16. The coil l on one shank of 20 an electromagnet has passing through it a weak current and that on the other shank l' a strong current, in the circuit of which the carbon is inserted. Above the electromagnet a spring-lever m is arranged, with which 25 a contact is connected. At the time of ignition a weak current is sent through the electromagnet, whereby m' is attracted, whereupon the contact is made by the spring 30 o , which has the effect of causing the lever m to oscillate like the striker of a gong and to detach the precipitates from the carbon by its repeated impact. When the arc has been removed to its terminal position, the powerful 35 current will pass through l' , attracting the end m^2 of the lever m . The primer may also be made to act on the carbons from above, for which purpose the latter may be provided at its upper end with a metallic contact o' , 40 Fig. 18.

A regulating and priming arrangement for arc-lamps of the kind described with parallel or obliquely placed carbons is shown in Figs. 17 and 18. In these figures, $a a'$ are the carbons, which are arranged so as to slide easily 45 in tubes. They are held in position by clamping-levers p with the aid of springs q . The levers p carry an armature which is attracted by the electromagnet r , so that at a given 50 moment the levers on both carbons may be eased, so as to allow the latter to drop. Below the plate P a second lever p' is pivotally arranged so that one of its arms can be turned sufficiently far to cause the carbon-points to 55 find a support on the lever end s . The movement of the lever is brought about by the electromagnet t acting on the armature r' , and thereby turning the lever-arm p' as far as necessary. The mode of action is as follows: 60 When the arc-lamps are thrown into circuit, a current is sent through the shunt-circuit, which passes through the coils of the electromagnet t , causing the armature r' to be attracted, thus turning the lever p' . At the 65 same time the electromagnet r , which is inserted in the same shunt-circuit, will attract

the armature with the two clamping-levers p , which will thus be made to release the carbons, permitting them to slide down until they are stopped by s . If s is a conductor, an 70 electric contact will at the same time be established and ignition will be effected, two small arcs being formed between s and the carbon-points. These will subsequently combine in one large arc as soon as s is withdrawn. The electric pressure in the shunt-circuit will then have been reduced so far that the lever p' can be brought back to its normal position by the action of the spring p^2 after the carbons have again been fixed in position or "clamped" by the levers p . Ignition having thus been effected by this arrangement, (which is advantageously done immediately at the points of the carbons,) the same arrangement may be applied for effecting periodical regulations. In this case the arrangement should be made so that in proportion as the carbon-points are consumed and the distance between them is consequently increased the tension in the arc increases to such an extent as to cause the shunt-current to become sufficiently powerful to set the above-mentioned arrangement in motion, thus permitting the carbons to shoot forward until arrested by the arrester or feed-check s , or else, in accordance with my former patent application, the arc as it ascends upward, owing to the consumption of the carbons, may make a direct contact, which will set the above-mentioned feed arrangement in action. For the purpose of regulation it is not requisite that the arrester or feed-check should be conductive. It is preferable to make it of non-conductive material, so that no arcs may be formed during the 90 periodical regulation. For the purpose of initial "priming" or ignition a conductive plate u may easily be interposed, by means of an electromagnet d , between the arrester or feed-check and the carbon-points, so that 100 in this case the ascending arrester may oppose to the carbon-points a metallic conductor unless the arrangement is made so that an independent metallic arrester is interposed in first "striking" the arc, so that 110 the carbon pencils may descend upon this, while for the purpose of the periodical regulation a second non-conductive arrester, likewise worked independently, is provided. The extreme ends of these arresters which are 120 brought into contact with the incandescent carbon may easily be made so that they can readily be detached and replaced when destroyed by the heat. The regulating mechanism is brought into action by causing the 125 arc to make a contact when it has ascended to a certain point through the consumption of the carbon pencils or by a shunt-magnet, which will establish the contact, setting the regulating mechanism in motion, owing to the 130 fact that the resistance of the arc increases as the distance between the obliquely-placed

carbons is increased through the consumption of their extreme ends or as the arc approaches nearer to the magnet, which serves to depress the arc.

5. What I claim, and desire to secure by Letters Patent, is—

1. In an electric-arc lamp the combination of a pair of downwardly-pointed parallel or converging carbons an arc between them a

10 reflector surrounding the carbon-points and having extensions or projections arranged in the direction of the arc for the purpose described and set forth.

2. In an electric-arc lamp the combination 15 of a pair of downwardly-pointed parallel or converging carbons an arc between them a reflector surrounding the carbon-points and having extensions or projections the carbons containing silicon or the like to reduce the 20 temperature of the arc for the purpose described and set forth.

3. In an electric-arc lamp the combination 25 of a pair of downwardly-pointed parallel or converging carbons an arc between them a reflector surrounding the carbon-points and having extensions or projections arranged in the direction of the arc and being constructed of non-conducting material for the purpose described and set forth.

30 4. In an electric-arc lamp the combination of a pair of downwardly-pointed parallel or converging carbons an arc between them a reflector surrounding the carbon-points and having extensions or projections arranged in the direction of the arc and a magnet producing 35 a magnetic field said field driving the arc against said projections of the reflector for the purpose described and set forth.

5. In an electric-arc lamp the combination 40 of a pair of carbons in alinement with each other an arc between them, a reflector surrounding the carbon-points and a projection arranged in said reflector of non-conducting material to hold the arc for the purpose described and set forth.

45 6. In an electric-arc lamp the combination of a pair of downwardly-pointed parallel or converging carbons an arc between them and the pole ends of a magnet arranged on each 50 side of the arc said pole ends being open or closed in order to produce lines of force parallel to the arc for the purpose described and set forth.

55 7. In an electric-arc lamp the combination of a pair of downwardly-pointed parallel or converging carbons an arc between them and the pole ends of a magnet arranged below the arc so as to pull it down for the purpose described and set forth.

60 8. In an electric-arc lamp the combination 65 of a pair of downwardly-pointed parallel or converging carbons an arc between them and the pole ends of a magnet arranged on each side of the arc said magnet being influenced by a series and a shunt coil the first being

placed above, the latter below the arc as and for the purpose set forth.

9. In an electric-arc lamp the combination of a pair of downwardly-pointed parallel or converging carbons and the pole ends of a magnet arranged on each side of the carbons and a primer arranged to strike the carbons above the points as described and for the purpose set forth.

10. In an electric-arc lamp the combination 75 of a pair of downwardly-pointed parallel or converging carbons and the pole ends of a magnet arranged on each side of the carbons and a primer operating over the points of the carbons, a lever *h* operating the primer, an 80 electromagnet operating said lever and springs to actuate the primer as described and for the purpose set forth.

11. In an electric-arc lamp the combination 85 of a pair of downwardly-pointed parallel or converging carbons a primer arranged to strike the carbon ends above their points said primer being operated by an electromagnet *l*, *l'* and a contact *n* and a spring *o* for the purpose described and set forth.

12. In an electric-arc lamp the combination 90 of a pair of downwardly-pointed parallel or converging carbons an arc between them a primer *h* loosely connected to a lever and adapted to strike the carbons from below or the side and a spring connecting the primer with said lever for the purpose described and set forth.

13. In an electric-arc lamp the combination 95 of a pair of downwardly-pointed parallel or converging carbons two primers being in conductive connection with each other and carrying a priming cross-bar said primer being attached to a lever and having a spring connection therewith as described and for the 100 purpose set forth.

14. In an electric-arc lamp a pair of downwardly-pointed parallel or converging carbons a primer *s* arranged to ignite the carbons from below and hold them while being released, a double-armed lever *p'* to operate 110 said primer an armature *r'* to operate said lever and an electromagnet *t* to operate said armature for the purpose described and set forth.

115 15. In an electric-arc lamp a pair of downwardly-pointed parallel or converging carbons a primer *s* arranged to ignite the carbons from below and hold them while being released, a double-armed lever *p'* to operate 120 said primer an armature *r'*, a lever *p* to hold the carbons having an armature influenced by a spring *q* an electromagnet *r* for operating said armature for the purpose described and set forth.
